INVENTOR
BY Benjamin Ross

W. P. Driswell,
ATTORNEY

UNITED STATES PATENT OFFICE.

BENJAMIN ROSS, OF BROOKLYN, NEW YORK.

SHOE SOLE.

Application filed August 30, 1922. Serial No. 585,225.

To all whom it may concern:

Be it known that I, BENJAMIN Ross, a citizen of the United States, and a resident of New York, borough of Brooklyn, in the county of Kings and State of New York, have invented certain new and useful Improvements in a Shoe Sole, of which the following is a full, clear, and exact specification.

This invention relates to footwear, and has for its object primarily to provide a sole for boots, shoes and the like designed to cushion the heel and support the arch of the foot of the wearer whereby comfort will be obtained by absorbing the impact of the tread of the heel together with enabling a natural movement of the instep and fore part of the foot while supporting the arch in its normal position. This is accomplished mainly by providing a flexible outer sole member having a foot portion, a shank portion and a concaved heel portion. On the upper face of the outer sole member may be an inner sole member also having a concaved heel portion disposed in the concavity of the outer sole member, and in the concavity of the inner sole member is an elastic inlay for cushioning the heel of the wearer. A partial rigidity is imparted to the flexibility of the shank portion of both sole members by providing therebetween a yielding stiffener or metallic strip disposed in spanning position on the shank portions, and one end of the strip is held to the foot portion of the outer sole member, while its other end is movable toward and from the concavity of the heel portion, in order to properly support the arch as well as permitting normal movements of the arch.

A further object of the invention is to provide a shoe sole of a simple, efficient and durable construction which may be made of appropriate material in any suitable size.

With these and other objects in view, the invention will be hereinafter more fully explained with reference to the accompanying drawing forming a part of this specification in which similar characters of reference indicate corresponding parts in all the views, and will then be pointed out in the claims at the end of the description.

In the drawing, Figure 1 is a plan of one form of shoe sole embodying my invention.

Fig. 2 is a sectional view taken on the line 2—2 of Fig. 1.

Fig. 3 is a perspective sectional view taken through the elastic inlay used in the sole.

Fig. 4 is an enlarged top plan of the yielding stiffener used in the sole, and

Fig. 5 is an enlarged sectional view taken on the line 5—5 of Fig. 4.

The device has an outer sole member 10 of leather or other suitable flexible material, and the sole may be of any appropriate shape and size having a foot portion 11, a shank 65 portion 12 and a heel portion 13 with a concavity 14 in its upper face for use on a shoe, boot or other footwear. On the upper face of the flexible base member 10 is an inner sole member 15 of a size and shape corresponding to that of the base member, and this inner sole member has a concavity 15^a disposed in the bottom of the concavity of the outer sole member.

In the concavity 15^a of the inner sole member 15, is an inlay 16 which may be made of rubber or other elastic material, and this yielding inlay has a curved convexed underside, as 17, conforming to the curvature of the concavity 15^a of the inner sole member, 70 while the upper face of the inlay is preferably flat, as at 18, and this inlay may be of a size so that its upper face is on a plane approximately similar to the level of the part of the shank portion, as 18^a, of the inner sole 80 member, in order to cushion the heel of the wearer whereby the impact of the tread when walking will be absorbed.

Partial rigidity is imparted to the flexibility of the shank portions of the outer and inner sole members by providing on the shank portion of the outer sole member under the inner sole member a stiffener, as 19. The stiffener preferably includes a bearing plate 20 of substantially a rectangular shape 95 with a tapered portion, as 21, extending from one of its ends. In opposite parts of the side edges of the plate 20 may be two notches, as 22, 23, so that when the plate is made of metal its end parts, as 24, 100 25, may yield under pressure. The bearing plate 20 is arranged on the shank portion 12

lengthwise of the sole members so that the tapered end 21 protrudes toward the foot portion of the members with the end part 24 being toward the elastic inlay 16, and the 5 end part 24 is secured to the base member by a bolt or screw 26, Fig. 2, being driven through a hole, as 27, provided in this end part. In the end part 25 of the plate 20 is a slot 28 disposed toward the tapered 10 portion 21 of the plate. The stiffener 19 also has a strip 29 of spring metal with one of its ends bearing upon the upper face of the end part 25 of the plate 20, and this yielding strip is movable on the plate lengthwise of the slot 28. The yielding strip 29 is disposed as well as being of a length so that it spans the shank portions of the sole members 10, and the second end of the strip is secured to the base member by a 15 screw or bolt 30 being driven through a hole 31 provided in the strip. The strip 29 is downwardly curved, as shown, to conform with the curvature of the shank portion of the outer sole member for serving 20 to support the arch of the foot of the wearer in its normal position and serving by its yielding action when under pressure to allow the bone of the arch of the foot of the wearer to move naturally when walking. 25 The strip is movably attached to the slotted end of the bearing plate 20 by the two depending clips, as 32, 33, which are provided on the underside of the end of the plate contacting with the bearing plate 20. The 30 clips are preferably in the forms of hooks which are struck-out of the strip and movably disposed through the slot 28 of the plate 20 with the free end parts of the hooks being bent in opposite directions so that they 35 are slidable on opposite parts of the edge of the slot. On top of the inner sole member may be a sock lining, as 34, commonly used in footwear.

In the foregoing description, I have embodied the preferred form of my invention, 40 but I do not wish to be understood as limiting myself thereto, as I am aware that modifications may be made therein without departing from the principle or sacrificing any 45 of the advantages of this invention, there-

fore, I reserve to myself the right to make such changes as fairly fall within the scope thereof.

Having thus described my invention, I claim as new and desire to secure by Let- 55 ters Patent:

1. A shoe sole having in combination, a flexible sole member with a shank portion and a concaved heel portion, an elastic inlay in the concavity of the sole member, a 60 stiffener on the shank portion of the member, said stiffener including a slotted bearing plate held in proximity to the concavity of the member, and a yielding strip extending lengthwise over the shank portion of the member, the strip having one of its ends secured to the sole member and having its other end movably contacting with the bearing plate as well as having depending hook members movably disposed through the slot 65 of the bearing plate.

2. A shoe sole having in combination, a flexible outer sole member with a shank portion and a concaved heel portion, an inner sole member on the upper surface of the outer sole member and having a concaved heel portion disposed in the concavity of the outer sole member, an elastic inlay in the concavity of the inner sole member, and a stiffener on the shank portion of the outer member under the inner sole member, said stiffener including a bearing plate held in proximity to the concavity of both sole members, a yielding strip extending lengthwise over the shank portion of the outer sole member, the strip having one of its ends secured to the outer sole member and having its other end movably contacting with the bearing plate, and means connecting the contacting parts of the plate and strip 80 whereby the strip may move toward and from the heel portion of the sole, but will be prevented from transverse movement.

This specification signed and witnessed this 29th day of August, A. D. 1922.

BENJAMIN ROSS.
